ADJUSTABLE FURNITURE

Filed July 5, 1928

UNITED STATES PATENT OFFICE

WAYNE F. ROSSITER, OF SAN FRANCISCO, CALIFORNIA

ADJUSTABLE FURNITURE

Application filed July 5, 1928. Serial No. 290,654.

My invention relates to improvements in adjustable furniture, and it consists in the combinations, constructions and arrangements hereinafter described and claimed.

- 5 An object of my invention is to provide adjustable furniture designed to be used in printing offices. Up to the present time, type or plates have been locked in a chase by furniture, i. e. small pieces of wood, and quoins. 10 Considerable difficulty is experienced in locking the cut in place if the cut is secured in a chase on a bias. A number of pieces of furniture have to be cut in different sizes and lengths in order to have these contact with the 15 inclined sides of the cut.

The principal object of my invention is to provide an adjustable piece of furniture which has two opposed edges that may be swung at an angle with respect to each other 20 so that one edge can engage with the cut while the other contacts the furniture or the side of the chase.

A further object of my invention is to provide a device of the type described which is 25 extremely simple in construction and which consists of two pieces identical in shape and designed so that they will interlock with each other when placed in the chase.

Other objects and advantages will appear 30 as the specification proceeds, the novel features will be particularly pointed out in what I hereinafter claim.

My invention is illustrated in the accompanying drawing forming a part of this application, in which

35 Figure 1 is a top plan view of a chase showing furniture, quoins and a cut disposed therein, and also showing a number of the adjustable pieces of furniture disposed in position;

Figure 2 is a top plan view of the device;

Figure 3 is a section along the line 3—3 of Figure 2;

40 Figure 4 is a section along the line 4—4 of Figure 2; and

Figure 5 is a perspective view of one of the members forming the device.

In carrying out my invention, I provide 45 two identical members indicated generally

at A and B, both being identical to each other. A description of one will therefore suffice.

The member B has a central circular-shaped portion 1 and a base 2. The portion 1 is one-half the thickness of the base 2, and the portion is provided with a bevelled edge 3 that extends through an arc of 180°. The base 2 has recesses 4 and 5 cut therein, these recesses having edges 6 and 7 that are of the same height as the width of the portion 1.

5 The member B has a bevelled groove 8 cut therein in the base 2 for receiving the bevelled edge 3 of the member A. The base is provided with curved edges 9 and 10 and a curved edge 11 that coincides with the curved portion 1 of the member A. The bevelled groove is cut into the curved edge 11.

60 Figure 5 shows a perspective view of the member B. It will be noted from this figure that the portion 1 projects from the base 2 and then the surface 12 of the portion 1 contacts with a similar surface of the member A. This figure further shows the curved edges 9 and 10 and the curved edge 11, the latter having the bevelled groove 8 cut therein.

65 From the foregoing description of the various parts of the device, the operation thereof may be readily understood.

70 The two members are placed one on top of the other as shown in Figure 2, and Figure 3 shows how the bevelled edges 3 of each member enter the bevelled grooves 8. The edges and grooves are portions of circles, and therefore the member A may be swung with respect to the member B into various positions as 75 shown in Figure 1. The recesses 4 and 5 permit the member to be swung into rather extreme angles.

80 Assume that a cut indicated at 13 in Figure 1 is to be placed on a bias in a chase 14. Furniture indicated generally at 15 is built up in the manner shown, and then my adjustable furniture is placed at the points C, D. and E for contacting with the inclined edges of the cut. The edges 16 of the bases 2 contact with the sides of the cut and with the furniture. Quoins 17 are used for tightening up the furniture, and these quoins will cause the adjustable furniture to contact with the cut and hold it in position.

Although I have shown and described one embodiment of my invention, it is to be understood that the same is susceptible of various changes, and I reserve the right to employ such changes as may come within the scope of the invention as claimed.

I claim:

1. An adjustable furniture comprising two identical members pivotally secured to each other, the outer edges of said members being swingable into various angular positions with respect to each other.
2. An adjustable furniture comprising two identical members, each member having a circular portion and a circular groove for receiving the portion of the other member.
3. An adjustable furniture comprising two identical members, each member having a circular portion and a circular groove for receiving the portion of the other member, the edges of said portions being bevelled and the grooves being bevelled for causing the members to interlock with each other.
4. An adjustable furniture comprising two identical members, each member having a circular portion with a bevelled edge and a base portion, each base portion having a bevelled groove for receiving the bevelled edge of the other member.
5. An adjustable furniture comprising two identical members, each member having an arcuate portion rotatable on the other portion for permitting the opposed edges to swing into various angular positions, the thickness of the combined members remaining the same throughout all adjustments.

WAYNE F. ROSSITER.
